J. F. BOORAEM

METHOD OF PROTECTING CERAMIC SWIMMING POOL STRUCTURES

Filed Dec. 4, 1922

UNITED STATES PATENT OFFICE.

JOHN FRANCIS BOORAHM, OF GREENWICH, CONNECTICUT.

METHOD OF PROTECTING CERAMIC SWIMMING-POOL STRUCTURES.

Application filed December 4, 1922. Serial No. 604,647.

To all whom it may concern:

Be it known that I, JOHN FRANCIS BOORAHM, a citizen of the United States, and a resident of Greenwich, county of Fairfield, and 5 State of Connecticut, have invented certain new and useful Improvements in Methods of Protecting Ceramic Swimming-Pool Structures, of which the following is a specification.

10 This invention relates to an improved method of protecting ceramic swimming pool structures and more particularly finds its principal application to outdoor or exposed swimming pools. Heretofore, it has 15 not been possible for the contractor to guarantee outdoor pools constructed of glazed tile, terra cotta or other ceramic material against the injurious effects of frost or ice. In the winter, when the outdoor temperature is below the freezing point, snow or moisture collecting in crevices of the 20 ceramic tiling freezes and in expanding, frequently loosens or splits the tile and cracks the glazed surfaces thereof.

25 I propose, in the present invention to provide a method whereby the ceramic structures of such outdoor or exposed pools may be absolutely protected and insured against the destructive action of frost and ice. Not 30 only does my new method prevent the freezing of water or moisture upon or in the crevices of the ceramic structure, but as a resultant thereof, the space allotted to the swimming pool is converted into an ice skating rink, thus affording a source of revenue 35 during the winter, as well as in summer to the owner or proprietor.

In so far as this latter advantageous feature of the invention is concerned, it might 40 well be employed in connection with indoor pools. Thus in a building having a number of such ceramic pool structures utilized for purposes of bathing or swimming in the summer time, in the winter the proprietor 45 may readily convert any number or all of the pools into skating rinks. Thus patrons of the establishment are enabled to exercise their preference for either skating or swimming, or may enjoy both of these pleasures 50 without leaving the building.

With the above and other objects in view, the invention consists in the improved method which I shall presently describe in detail and thus subsequently incorporate in 55 the subjoined claims.

In the accompanying drawing I have

illustrated my improved method in connection with a ceramic pool construction of conventional type, the said drawing representing a sectional perspective view of the pool. 60

The pool structure as illustrated in the drawing is erected upon a foundation of reinforced concrete indicated at 5. The bottom wall 6, the side walls 7 and the end walls of the pool structure, are composed of 65 brick or tile, terra cotta or other ceramic material, the exposed surfaces of which are highly glazed. If desired, a backing wall of brick, indicated at 8, may be provided at the outer side of each of the end and side 70 walls. At the upper edge of each of the end and side walls of the pool, there is provided a combined gutter and life rail 9, these gutter and life rails being substantially continuous around the four sides of the pool. 75

In the present instance I have illustrated the pool as provided with a continuous trench 10 also extending around the entire pool structure which provides a convenient space for attendants in opening or closing 80 the drainage valves or making necessary repairs thereto. The upper side of this trench is closed by the marginal flooring 11 of the pool which is made up of ceramic tiles or slabs. It will be understood that the foregoing description of the pool construction is 85 merely illustrative and the present invention which I shall presently describe, is applicable as well to the numerous other constructions of such pools known to the present art or which may subsequently be conceived. In the described construction, there is interposed between the bottom, side and end walls of the pool and the concrete foundation, a heavy waterproofing material 90 shown at 12, said material also extending between the marginal floor slabs 11 and the parts of the foundation structure which support the same.

In the summer time when the pool is 100 employed for swimming purposes, the maximum water level is that indicated at A, or below the marginal flooring surrounding the pool structure. For the winter time when the pool can no longer be employed 105 for swimming purposes, the trench outlets from the gutters are closed and an embankment is constructed around the pool outwardly of the flooring 11. The adjacent surface of this embankment may extend 110 down to the flooring at a slope of any desired degree and this sloping face of the

embankment may be composed of turf, gravel or other suitable material which will resist a considerable pressure. However, when available, the pool structure may be 5 built within the boundaries of a natural embankment. The pool is then flooded with water to a considerable depth above the floor 11 and slightly below the upper level of the embankment. I have shown the embankment in the accompanying drawing at 10 13. When the temperature of the atmosphere is below 32° F., water will of course freeze and as the temperature decreases, a solid cake of ice, indicated at 14, will form 15 upon the water covering the pool structure between the walls of the embankment 13. In the drawing I have indicated the approximate thickness of the ice sheet which will form at normal winter temperatures. 20 However, the depth of the water above the marginal flooring 11 of the pool is such that even during intensely severe winters, the greatest thickness to which the ice will form will be approximately that indicated 25 by the broken line B, which it will be observed, is a considerable distance above the floor 11. Thus the temperature of the water below the ice will remain at 32° F. which will not have a harmful effect upon the 30 glazed ceramic tiling or any other lining, as there can be no expansion to produce rupture unless ice is formed. The coating of ice and water forms a blanket and prevents further freezing. The superimposed 35 water head thus affords a complete protection for the tile structure so that by the adaptation of my present method contractors may give an absolute guarantee against injury to outdoor pools during the winter 40 from the effects of frost or ice. At the same time, as the ice cake which forms upon the superimposed water head increases in thickness and can support the weight of a greater or less number of persons, it may be employed for the purpose of 45 ice skating, thus affording a source of winter revenue to the owner of the pool.

While the primary object and purpose of my present invention is to protect exposed 50 or outdoor swimming pools of ceramic construction against injury during the winter, my present method might also be advantageously employed by the proprietor of public indoor swimming pools. Thus if such 55 an establishment contains two or more such pool structures, one might be devoted to swimmers and the other to ice skaters, thus possibly increasing the patronage of such an establishment with a correspondingly increased revenue to the proprietor. Of course, in the latter instance, artificial means would be employed for the purpose of freezing the upper area of the superimposed water head to form the ice sheet. 60

65 In the use of the method in connection

with outdoor pools, after the temperature has moderated and the ice sheet melted in the spring, the excess water is drawn off so that the level of the water is again lowered to the line A. The surrounding embankment 13 can either then be removed, if of a temporary character, or if permanent, terraced and seeded for grass and steps may be cut therein, or other suitable means provided for the convenient descent 70 of swimmers to the marginal floor 11 of the pool. While I have above referred to an embankment 13 surrounding the pool structure, it will be understood that other means confining the superimposed water head and which may therefore be considered as the equivalent of such an embankment, may be provided. However, I prefer to adopt natural means for the purpose of confining the water head wherever 75 possible, since in such case it is not necessary to provide means for compensating for expansive forces. Accordingly, it is to be understood that in the practice of my new method, I do not consider myself as limited to the precise detail features herein described but reserve the privilege of making any necessary changes therein as may be necessitated by existing conditions or peculiarities of the pool structure or surrounding land area, and as may be fairly considered as within the spirit and scope of the invention as claimed. 80

I claim:

1. The herein described method which consists in superimposing a water head upon a swimming pool structure and subjecting the upper area of the superimposed water head to a freezing temperature to form an ice sheet having a thickness appreciably less than the depth of the superimposed water head. 100

2. The herein described method which consists in confining a superimposed water head upon a ceramic swimming pool structure and subjecting the upper area of the superimposed water head to a freezing temperature whereby a sheet of ice is formed of a thickness capable of use as a skating rink and said water head providing a body of water intervening between the ice sheet and the upper marginal surface of the pool having a temperature of approximately 105 32° F. 110

3. The method of protecting outdoor swimming pools of ceramic construction, which consists in surrounding said pool by an embankment and flooding the pool with water above its normal summertime water level to provide a superimposed water head between the walls of the embankment of such depth that the greatest thickness of the ice sheet forming on said superimposed water head will be less than the depth of the water head to thereby provide an inter- 115 120 125 130

- vening body of water between the ice sheet and the upper surface of the pool structure having a temperature of approximately 32° F.
5. 4. The method of protecting swimming pools of ceramic construction, which consists in surrounding the pool by an embankment, and then freezing a body of water between the walls of said embankment to form 10 an ice sheet of sufficient thickness for use as a skating rink and having its lower surface spaced an appreciable distance above the marginal surface of the pool structure.
5. The method of protecting swimming 15 pools of ceramic construction which consists in surrounding the pool proper with en-
- closing walls and then flooding the pool to provide a depth of water between said walls above the maximum water level in the pool when used for swimming purposes, sufficient 20 to maintain a temperature of approximately 32° F. of the water in immediate contact with parts of the pool while permitting the upper area of the flood water to be frozen by natural or artificial means to produce an 25 ice sheet of a thickness requisite for use as a skating rink.
- In testimony that I claim the foregoing as my invention, I have signed my name hereunder.

J. FRANCIS BOORAEAM.
